5 Claims

The present invention relates to a clip mounted label dispenser for removing adhesive labels from a liner, and more specifically the invention resides in the combination of a mounting clip which supports a stripping edge, and a liner guide member shaped to fit over the stripping edge so that a liner bearing adhesive labels on it may be pulled between the liner guide and the stripping edge to separate the labels from the liner.

Adhesive labels of the sort that may be used on filing folders, or mailing envelopes are frequently packaged by adhering a row of them on a continuous strip of release coated, liner material. As the labels are to be used, the secretary or clerk pulls the labels from the liner manually. The need to remove the labels from the liner can be, at least, a nuisance, and where labels such as these are used in large numbers, it can get to be a costly waste of man hours. On the other hand, such labels are quite inexpensive and they are rarely used in the vast quantity necessary to justify the purchase of expensive mechanical devices for removing them.

The present invention provides a very inexpensive device that can be made from two, stamped, sheet metal members, and that will conveniently and efficiently strip such labels from their liner sheets. Moreover, the present invention is designed to clamp over a divider, or a wall of a desk drawer, or a side of a box, so that it can be conveniently located at the receptacle where the labels are stored, and it does not clutter up desk top or table top surfaces, either when it is in use, or when it is idle.

Accordingly, the salient objects and advantages of the present invention may be summarized as follows:

To provide an efficient and convenient means for dispensing adhesive labels from a liner strip.

To provide an inexpensive device for stripping adhesive labels from a liner strip.

To provide an effective device for easily stripping adhesive labels from a liner strip, which device can be simply mounted on a desk drawer, or other storage receptacle for the labels so that it does not clutter work surfaces either when it is used, or when it is idle.

In the portion of this specification that follows and that precedes the claims, there appears a detailed written description of the invention, and of the manner and process of making and using it in such full, clear, concise, and exact terms as to enable any person skilled in the art to which it pertains, or with which it is most nearly connected, to make and use the same. The following description also sets forth in one preferred embodiment the best mode presently contemplated by the inventor for carrying out this invention. However, the detailed description which precedes the claims is not intended as a measure of the extent of the invention, but, on the contrary, the subject matter which the inventor regards as the invention is particularly pointed out and distinctly claimed in the claims which appear in the conclusion of this specification, after the description of the preferred embodiment.

In the drawings:

FIG. 1 is a front elevation of the preferred embodiment of the invention;

FIG. 2 is a side view in section taken along line 2—2 in FIG. 1;

FIG. 3 is a top plan view of the embodiment shown in

2

FIG. 1 illustrating the passage of a liner strip with labels through the dispenser of this embodiment,

FIG. 4 is a view in section of the embodiment shown in FIG. 1 taken along the line 4—4 in FIG. 1,

FIG. 5 is another view in section of the embodiment shown in FIG. 1 taken along the line 5—5 in FIG. 1, and

FIG. 6 is an isometric view of the preferred embodiment of the invention illustrated in FIGS. 1 through 5.

In the embodiment shown in the drawings, the dispenser 10 of the present invention is mounted on a supporting member 2, which may be a divider in a desk drawer, a wall of the desk drawer, a side of a box, or some other such vertical structure. The dispenser 1 is secured to the supporting member 2 by a mounting clip 3 which is made up of a single piece of stamped sheet metal formed so that it has a pair of spaced apart clamping wings 4 and 5 that are joined together at their top ends by a horizontal portion which serves as a liner support 6. The clamping wings 4 and 5 are resilient and biased toward one another so as to grasp the supporting member 2 securely between them, and the front clamping wing 4 has a recessed crease 7 in its bottom end and a flaring lip 8 along its bottom end to facilitate its mounting on the supporting member 2. The corner formed at the top of the front clamping wing 4 where the liner support 6 and the clamping wing 4 meet serves as a stripping edge 9.

A liner guide 10 is stamped from a second piece of sheet metal and shaped to conform about the stripping edge 9. Hence, the liner guide 10 is an elongated strip of sheet metal having an L-shaped cross section and fitting over the liner support 6, the stripping edge 9, the front clamping wing 4 adjacent to the stripping edge 9. The liner guide 10 also has a hinge leaf 11 which extends over one corner of the rear clamping wing 5 adjacent to the liner support 6, and it has a latching leaf 12 which extends over the opposite corner of the top end of the rear clamping wing 5 adjacent to the liner support 6. The latching leaf 12 is biased inwardly to engage the rear clamping wing 5 and its lower end is flared outwardly so that it may be readily slipped over the clamping wing 5. A hinge pin 13 with its ends riveted is mounted in aligned holes which respectively pass through the hinge leaf 11, the back clamping wing 5, the front clamping wing 4 and the vertical extension 14 of the liner guide 10 adjacent to the front clamping wing 4. At the other end of the vertical extension 14 of the liner guide 10 a latching detent 15 is formed opposite to the latching leaf 12 to press into a latching hole 16 drilled in the front clamping wing 4.

Aligned with the latching detent 15 and in the horizontal extension 17 of the liner guide 10 parallel with the liner support 6 is a spacing detent 18 which rests on the liner support 6 when the liner guide 10 is in its lower position about the stripping edge 9. An ejection slot 19 is cut in the liner guide 10 opposite to and aligned with the stripping edge 9 and extending most of the length of the liner guide 10. A handle 20 is stamped out of the vertical extension 14 of the liner guide 10 to project forwardly therefrom, and flared lips 21 and 22 are formed on the opposite edges of the vertical extension 14 and the horizontal extension 17 of the liner guide 10.

To use the dispenser 1 shown in the drawing, the mounting clip 3 is slipped over a suitable vertical support member 2, and the liner guide 10 is pivoted upwardly around the hinge pin 13. Then, a liner 23 having labels 24 on it is laid over the liner support 6, and the liner guide 10 is pivoted downwardly about the hinge pin 13 until it latches in its operating position when the latching detent 15 finds the latching hole 16. Then an end 25 of the liner 23 extending below the vertical extension 14 is grasped and pulled, drawing the liner 23 with labels 24 on it, through the space between the horizontal extension 17

of the liner guide 10 and the liner support 6, and through the space between the vertical extension 14 of the liner guide 10 and the front clamping wing 4. When the liner 23 reaches the stripping edge 9 and passes over it under the vertical extension 14 of the liner guide 10, the stiffer labels 24 separate from the release coated liner 23 and are ejected outwardly through the ejection slot 19, where they are presented free of the liner and ready for application.

It will be apparent from the foregoing description, that the present invention provides a unique, convenient, very inexpensive but extremely helpful device for users of adhesive labels. It may be permanently mounted, or easily mounted and dismounted whenever needed. It is rugged and almost incredibly simple to use. However, it will also be apparent to anyone skilled in the art that many variations can be made in the embodiment shown and many other embodiments devised, which, though they depart from the embodiment shown, nevertheless employ the invention described. Therefore, the invention is not limited to that embodiment, but is rather set forth in the claims that follow.

I claim:

1. A clip mounted label dispenser for removing adhesive labels from a liner comprising the combination of 25
a mounting clip having a pair of spaced apart clamping wings arranged side by side and connected together at one end to receive a supporting member between them;
a stripping edge supported by said mounting clip and 30 shaped to support a liner passing over it and to cause adhesive labels on said liner to separate from said liner as said liner moves over it;
and a liner guide shaped to fit over said stripping edge and said liner strip over said stripping edge to force 35 said liner to follow closely over said stripping edge and having a label ejection slot aligned with said stripping edge to permit said labels to eject from said stripping edge as said labels separate from said liner.
2. A clip mounted label dispenser as set forth in claim 40
1 wherein
said clamping wings are resilient members biased toward each other to grip said supporting member between them.
3. A clip mounted label dispenser as set forth in claim 45
2 wherein

a liner support member, which joins and is integral with said clamping wings at adjacent top ends of said clamping wings, connecting said clamping wings together;

and said stripping edge is formed by a corner where said liner support member joins one of said clamping wings.

4. A clip mounted label dispenser as set forth in claim 1
wherein

said liner guide is hinged at one end to said mounting clip, has latching means at another end to secure it over said stripping edge, and has a spacer to retain it in spaced relationship to said stripping edge to permit said liner and labels to move easily between it and said stripping edge.

5. A clip mounted label dispenser as set forth in claim 3
wherein

said liner guide is a stamped metal strip having an L-shaped cross section to conform to said stripping edge and to said liner support and said one of said clamping wings adjacent to said stripping edge; said liner guide also has a hinge leaf at one end passing over a portion of the other of said clamping wings adjacent to said liner support member, and has a latching leaf at its other end passing over and resiliently engaging a portion of said other of said clamping wings;

a hinge pin is mounted through aligned holes in said liner guide, said pair of clamping wings and said hinge leaf;

and a latching detent is formed in said liner guide opposite said latching leaf to engage a hole formed in said one of said clamping wings when said liner guide is in place over said stripping edge.
